UNITED STATES PATENT OFFICE.

LLOYD G. SCHIMMEL, OF LOS ANGELES, CALIFORNIA, ASSIGNOR TO PERFECTION
FAUCET MFG. CORP., A CORPORATION OF NEVADA.

FAUCET AND PROCESS OF MAKING SAME.

Application filed October 11, 1928. Serial No. 311,818.

This invention relates to faucets particularly adapted for application to water service lines. A principal object of invention is to provide a simple and economical, leak-proof 5 faucet arranged to be quickly opened and closed and having a valve therein opposed to the passage of a liquid therethrough, so that the pressure on the inlet side of the faucet will serve to seat the valve and prevent leakage of the liquid from the spout under normal 10 conditions.

A principal object of invention also is to provide a faucet having an integral body and spout so designed that it may be die-cast in 15 molds for the purpose of reducing the manufacturing cost, and further to provide a process for producing faucets by die-casting. In order that this may be done, it is necessary to so arrange the openings in the body that cores 20 may be withdrawn from the mold subsequent to a casting operation, and at least one of said openings may be closed permanently to present a finished appearance to the faucet.

Heretofore in the construction of faucets 25 it has been found necessary to sand cast the faucets, and it is well known that castings produced in this manner require a substantial amount of finishing in order to polish and plate the castings. The obtaining methods 30 are therefore expensive and the weight of the finished article is usually excessive.

Accordingly, it is an object of my invention to provide a type of faucet which can be molded in a die casting operation of a 35 suitable metal, so that when completed a minimum expense only is necessary in finishing castings preparatory for use, and the finished article will be of minimum weight and consequently made at a minimum expense.

It is a further object of this invention to 40 provide a faucet which is free from unnecessary and complicated parts, gaskets, washers and the like, which are susceptible to wear and corrosion and consequently cause trouble in the operation and use of the faucet.

This application is a continuation in part 45 of my application, Serial Number 242,589, filed December 27, 1927, for faucets.

The details of my improvements will be 50 hereinafter explained, and are shown clearly in the appended drawings, in which:

Fig. 1 is a sectional elevation of a faucet embodying my improvements;

Fig. 2 is a sectional plan of the same on line 2—2 of Fig. 1.

Fig. 3 is a sectional plan of the same on line 3—3 of Fig. 1.

Figs. 4 and 5 are fragmentary sections of the body of the faucet showing the method and means for closing one of the core recesses 60 in the body by means of which the passage in the spout of the faucet is cored in a die casting process.

Fig. 6 is a sectional elevation of a faucet after the casting operation but before the 65 cores have been withdrawn.

Fig. 7 is a section on the line 7—7 of Fig. 6.

Fig. 8 is a detail showing one form of a core used in my process of making a faucet.

Referring to the drawings, the body 10 has 70 a flanged bottom portion 11 adapted to rest against a suitable supporting member for the faucet, such as a wall or a basin. From the base of the body 10 is extended an integrally formed threaded stem 12 having an inlet 75 passage 13 therein communicating with an inlet chamber 14 which is in turn in communication with central chamber 15 in the body 10. It will be noted that the inlet passage 13, inlet chamber 14 and central chamber 15 are 80 preferably concentric and of progressively greater diameter, forming annular shoulders or ledges 16 and 17, shoulder 16 being formed between inlet passage 13 and inlet chamber 14, while shoulder 17 is formed between inlet 85 passage 14 and central chamber 15.

The body 10 has an integrally formed spout 18 extended at right angles to the axis thereof, with an angularly formed delivery nozzle 19. The spout 18 has a cored passage 20 formed 90 therein which opens into the chamber 15 of the body and is transversely aligned with an opening 21 formed in the wall 22 of the faucet body. This opening 21 is in communication with central chamber 15 and positioned 95 diametrically opposite spout 18, the passage 20 and opening 21 being of circular, elliptical or any other cross-section, depending upon the desired form and shape of faucet spout.

The opening 21 may be left unsealed as by 100 my construction no water can pass into opening 21, thus rendering it unnecessary to seal the same against leakage of water therethrough. However, for the sake of the appearance of the finished faucet the opening 105 21 may be sealed in any suitable manner. As

shown in the drawings, the opening is sealed by means of a disc 23, which is formed of sheet metal, may be of circular, elliptical or other outline, and is of concave cross-section, as shown in Fig. 4.

The outer side of the body wall 22 is countersunk at the opening 21 to provide the annular shoulder 24 and cylindrical inner wall 25 of a counter-recess 26 of slightly greater diameter than the opening 21. Member 23 when positioned as shown in Fig. 4 is forced inwardly against shoulder 24 by means of a suitable die or tool until it assumes a flat cross-section, as shown in Fig. 5.

15 In the closing operation the flattening of the member 23 will cause the edges of said member to cut an annular groove 27 into the cylindrical wall 25 thereby firmly seating the same in the metal at the periphery of the 20 counter-recess 26 and against the shoulder 24, so as to form a permanent closure for the opening 21. It will be understood, of course, that the member 23 is of substantially harder and denser metal than the die casting metal of 25 which the faucet is made.

The body 10 has an internally threaded nipple 28 which is adapted to receive an externally threaded portion 29 on the cap 30, so that said cap may be threaded into the 30 portion 28 until the hexagonal portion 31 of the cap abuts the outer end of said portion 28, in which position the threaded portion is in abutting relation to a valve carrying member, hereinafter described, to force the 35 latter downwardly into water tight position.

Cap 30 is internally threaded to receive a screw 32 which is integrally formed on the inner end of a stem 33 to which is attached an operating handle 34 of suitable character. 40 Handle 34 may be removably secured to the stem 33 by means of a set screw 35 threaded into a member 36 rigidly secured to handle 34. Cap 30 is provided with a counterbored recess 37 formed within the portion 29 thereof, providing a shoulder 38. A head 39 carried on the inner end of the stem 33 adjacent the screw 32 is movable in the recess 37 and may be retracted upwardly against shoulder 38 by means of screw 32 operated 50 by handle 34.

The valve supporting member 40 is held against upward movement in central chamber 15 by means of screwing down cap 30 to abut the upper end of member 40 thereby 55 forcing the member 40 downwardly to seat the lower end of member 40 on a gasket 40' resting on shoulder 11 to make a water tight joint, preventing fluid from inlet chamber 14 passing up into opening 21 around member 40. The valve supporting member 40 is 60 stationarily held against rotary movement in central chamber 15 of the body 10 by means of a key, as at 41 in Fig. 2. Member 40 is arranged to slidably support a valve 42 having a stem 43 and has a tapered valve seat

44 adapted to receive and seat a valve packing member 45 held inwardly of the head of valve 42. The valve seat 44 communicates with a central chamber 46 which has an outlet port 47 communicating with the chamber 70 15 and with the passage 20 of the spout 18, so that water or other liquid may be directed from the inlet 13 through chamber 14 of the body 10, valve seat 44, chamber 46, port 47, and chamber 15 to the spout flowing out 75 through passageway 20 of spout 18 and through passageway 48 of delivery nozzle 19, when the valve is open. By means of the key 41, the port 47 is positively alined with the 80 spout passage 20.

The stem 43 of valve 42 is slidably held in a bore 49 in the upper portion of member 40, and when the valve 42 is closed, as shown in Fig. 1, the upper end of said stem 43 will project upwardly into the chamber 37 of the cap 30 so as to be readily engaged by the head 39 of stem 33 when the handle 34 is operated for screwing the screw 32 inwardly in the cap 30.

85 Valve 42 is operated in opposition to the pressure of water in the passage 13 and the chamber 14, which serves to normally hold the valve closed, as shown in Fig. 1, when the handle 34 is in open position and the head 39 connected therewith is disengaged 90 from the valve stem 43.

A particular feature of the present invention is the provision between the members 30 and 40 of a shallow chamber 50 in communication with the chamber 37, and adapted to 100 receive whatever volume of water may find its way through the passage 49 of member 40 and around the valve stem 43.

It will be observed that said chamber 50 is in open communication at all times with 105 the passage 20 of the spout, by means of a shallow passage 51 formed on the upper end of the member 40 and extending downwardly at an angle, so that when water is flowing through the member 40 and outwardly 110 through the spout passage 20, a flow of the water from the chamber 50 will be induced and said chamber will be relieved of any pressure which might otherwise be created therein, and which would serve to prevent the complete closing of the valve 42.

115 Referring particularly to the steps involved in producing my faucet, I locate cores 60, 61, 62 and 63 in a die-casting mold in the position shown in Fig. 6 of the drawing. As 120 shown in Fig. 6 of the drawing, the core 60 is so positioned as to form the central chamber 15 in the body 10 of the faucet, while a core member 64, integral with core 60 forms the inlet chamber 14. As indicated in Fig. 6 the core 60 has an opening therethrough which may be elliptical in cross-section as shown at 65 in Figs. 6 and 7 to receive elliptical cross-section core 62 or may be circular in cross-section to receive a core 66 of circu- 125 130

lar cross-section as shown in Fig. 8 of the drawings or may be of any other desired cross-section depending on what cross-section is desired for the spout 18. The core end 67, 5 integral with the core 62, extends through and projects a short distance beyond the core 60, so that the one-piece core 62 forms the spout passageway 20 and simultaneously also the opening 21 in the body wall 22.

10 The opposite end of the core 62 has a mitred face as indicated by 68. Abutting this mitred face 68 is the mitred face 69 of the core 63 which forms the curved or bent terminal portion 19 of the spout. It will be 15 understood that each of the cores 63 and 62 has a slight draft to permit ready removal thereof after the casting operation which is likewise facilitated by reason of the angular portion 70 at the point where the curved terminal portion merges into the straight portion of the spout to permit the withdrawal of the core 63 towards the left as shown in the drawing. The core 61 is preferably separate from the core 64 which is integral with 20 core 60, in which case 71 indicates the line on which the abutting faces of the two cores 61 and 64 come together. However, the cores 61, 64 and 60 may be all formed integral and withdrawn in one piece in an upward direction 25 looking at the position of the parts illustrated in Fig. 6.

After the molten metal has been poured in the mold around the cores, the cores are removed in the following order. The core 62 30 is first withdrawn toward the left through the opening 65 formed in the core 60 and through the opening 21 in the body wall 22. Simultaneously or prior or subsequently to the removal of this core 62 the terminal core 40 63 may be removed. After the core 62 has been withdrawn the core 60 is free to be withdrawn upwardly, carrying with it the core 61 in case these cores 61 and 62 are made integral. In the event of core 61 being separate 45 from core 60, core 61 would be withdrawn downwardly whereas core 60 with its integral part 64 would be withdrawn upwardly as seen in Fig. 6.

Particular attention is called to the die-casting of a spout orifice in the form of a radius or curve, as shown in the drawing by the spout 18 and orifice 19 of a faucet, by means of the use of steel cores.

It is desired to emphasize especially one 55 of the features of my invention and that is the die-casting of a hollow curve or radius that is necessary in the casting of a faucet that requires the usual curved spout or outlet for the liquid.

60 On the other hand, by my invention, I have made possible the withdrawal of a straight core through the body of the faucet, necessitating an opening in the body which can be sealed by an expansion plug or screw or 65 threaded plug or other suitable means.

By my invention, I am enabled to produce a cheap product, economical both as to time and material used and producing a finished article in one operation not possible by old methods hitherto employed in this art.

70 By my die-casting process, faucets may be produced at a maximum quantity production with a minimum of cost, eliminating the necessity of costly machining and finishing operations hitherto necessary in the case of sand castings and resulting in a perfectly formed faucet of appearance superior to faucets formed in any other way.

75 Thus, it will be observed that I have provided an improved type of faucet embodying 80 characteristics of design not heretofore used or employed in such devices, and that the structural arrangement and details thereof are simple and capable of ready adjustment and dis-assembling for necessary repairs or 85 adjustments.

I conceive it to be possible to modify the structure within the scope of the appended 90 claims without departing from the spirit of my invention.

What I claim is:

1. The process of producing a faucet having a body provided with a central chamber and also having a spout provided with a main straight portion and a bent terminal portion, comprising so locating a plurality of cores in a die, in angular relation, as to form desired sections, with a main-straight-portion-forming core extending through an opening in and projecting beyond a central-chamber-forming core to extend through what will be an opening in a wall of said body, and with a bent-terminal-portion-forming core meeting said main-straight-portion-forming core in mitre fashion to produce said bent terminal portion, pouring molten metal around said cores in the die, drawing said main-straight-portion-forming core through said opening in said central-chamber-forming core and through said opening in said wall 100 of the faucet, and drawing said terminal-portion-forming core and said central-chamber-forming core.

2. In a faucet, the combination with a die-cast body having a central chamber therein, 115 of an inlet stem provided with an inlet passageway in communication with said central chamber, an outlet spout having a main portion extending substantially at right angles to said inlet stem and provided with a main passageway in communication with said central chamber, said outlet spout also having a terminal portion provided with an orifice passageway in communication with and in angularly disposed relation to said main passageway, said body, inlet stem and outlet spout, said spout, comprising both main portion and terminal portion, being all integrally die cast, said body having one of its walls 120 provided with an opening in alignment with 125

said inlet passageway, said body having another of its walls provided with an opening in alignment with said main passageway, and a closure in said second named opening for 5 permanently closing the same to give a finished appearance to said faucet, said body being provided with an inlet chamber positioned between said inlet passageway and said central chamber, said inlet chamber having 10 a diameter intermediate the diameters of said inlet passageway and said central chamber, forming upper and lower annular shoulders between said central chamber and said inlet chamber and between said chamber and said inlet passageway, respectively, 15 a cap threaded in said first named opening,

a valve member snugly fitting in said central chamber, and having its bottom resting on said upper annular shoulder, a water tight joint therebetween being produced by the downward pressure of said cap on the top of said valve member, preventing the passage of fluid from said inlet chamber up into the chamber formed between said valve member and said closure, a valve co-operating with 20 said valve member and having a valve stem projecting upwardly through and beyond said valve body, and a handle-operated-head movable in a chamber in said cap for engagement with said valve stem to open said valve.

LLOYD G. SCHIMMEL.
